PROCESSING OF PLYWOOD PANELS TO EMBOSST ONE FACE THEREOF

Rehbeck Lewis, South Pasadena, and Clifford T. McElroy,
Temple City, Calif., assignors, by mesne assignments,
to Sierra Lumber Products, Pasadena, Calif., a corporation of California

Application November 12, 1949, Serial No. 126,724

7 Claims. (Cl. 154—106)

This invention relates to the processing of plywood panels to provide embossments on one outer face thereof.

Plywood panels comprise three or more plies and in commerce are produced in several grades, the gradings being determined by the proportion, to the area of a panel, of the total area of voids in the inner or bottom plies. Such voids, in the main, result from knots becoming dislodged. The better grades of panels have no or fewer knot-holes. It will be evident, however, that the better grades of panels are the more expensive and most difficult to produce because of the great amount of sorting and care attending the manufacture.

The present invention contemplates embossing the outer face of the upper ply of a plywood panel to provide a decorative construction or wall-lining element. The major problem attending the production of embossed panels results from the mentioned knot-holes, since the embossing pressure employed tends to inwardly flex those portions of the upper ply that are above the knot-holes. Consequently, said portions do not "take" the embossments and the panel is strewn with a multiplicity of smooth or "bald" spots, rendering the same unsightly. Of course, knot-hole-free panels would give desired results, but the expense involved in first paying the increased cost of such high grade panels and the further expense attending careful inspection, as by fluoroscoping, to discover such knot-holes that may be present even in high grade panels, raises the cost of the product so that the same cannot economically compete on the open market.

An object of the present invention, therefore, is to provide a novel method and apparatus for producing properly embossed panels regardless of the number and size of the knot-holes in the inner and lower plies to thereby provide a desired product at relatively low cost.

As a result of the present embossing method, not only the depressed portions of the upper ply are hardened, but also the raised portions are compressed to be harder than the original hardness of the panel. The above is in contradistinction to results obtained by prior methods, either by embossment or by removal of material to leave alternate high and low areas or stripes.

Another object of the invention, therefore, is to provide novel and improved apparatus for producing an embossed plywood panel which has an outer face, all portions of which are harder than the initial or original hardness of the outer ply of the panel.

A further object of the invention is to provide an embossed plywood panel in which the embossments are uniformly impressed throughout the entire surface thereof and which is adapted to be produced in a continuous commercial process at low cost.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a cross-sectional view of apparatus em-

2

bodying novel features and adapted to produce plywood panels according to the present invention.

Fig. 2 is a vertical sectional view of the machine shown in Fig. 1, together with a schematic showing of means for heating a portion of said machine.

Fig. 3 is an enlarged sectional view showing an old and usual method for embossing, and indicating how an unembossed area will result above a knot-hole in the middle ply of a three-ply panel being embossed.

10 Fig. 4 is a similar view, the same being taken on line 4—4 of Fig. 2, and indicating how the present means will effect proper embossment of an area above a comparable knot-hole.

Fig. 5 is a sectional view as taken on line 5—5 of Fig. 4.

Fig. 6 is a view similar to Fig. 4, and indicating the parts in the position they assume when the bottom ply of the panel contains a knot-hole.

20 Fig. 7 is a further enlarged sectional view, showing the manner in which the entire embossed surface of the panel is hardened during embossment.

The apparatus shown in Figs. 1 and 2 comprises, generally, a machine having rolls 10 and 11 between which a plywood panel 12 is adapted to be passed, means 13 optionally provided, for straightening the panel after embossment thereof, and means 14 for supplying heated fluid to roll 10. One or both rolls may be driven so as to effect feeding of a panel therebetween. A generally conventional support frame 15 for the rolls includes upper bearings 16 for roll 10 and adjustable bearings 17 for roll 11. Adjustable pressure between the rolls is afforded as by adjusting screws 18 engaged with bearings 17.

While the roll 11 has solid trunnions 19 that engage in bearings 17, roll 10 is provided with hollow or tubular trunnions 20 that communicate with the hollow interior 21 of the latter roll. A swivel 22 extends from each trunnion 20 and said swivels are connected, by conduit lines 23, to the heated-fluid supply means 14. Consequently, a continuous supply of hot oil 24, maintained at approximately 500° F. to be a little below the flash point, is circulated by means 14 through the hollow 21 of roll 10 to heat the cylindrical wall 25 of said roll.

Roll 10 is made of a suitable metal such as iron or steel and, in practice, cylindrical wall 25 is relatively thick for the dual purpose of imparting non-sagging rigidity to the roll, and absorbing and retaining heat supplied by the hot oil 24. The outer surface of roll wall 10 is provided with a series of circumferential lands 26 (Fig. 4) that may be formed in accordance with the design desired to be impressed into the panel 12. Said ridges may be continuous or interrupted; uniform or variable; and deep or shallow, according to the design desired. In any case, all or a major portion of said lands 26 are rounded in cross-section as are also the grooves 27 that alternate with the lands for reasons later apparent.

Roll 11 may be solid but is preferably hollow to avoid excess weight, the cylindrical wall 28 thereof being thick as before. According to the invention, said roll 11, about its wall 28, is provided with a layer 29 of a resilient material that, rather than being merely compressible, is also flowable. Certain synthetic rubbers have the property of being substantially non-compressible when confined. However, when unconfined, pressure against one portion will cause compression of that portion and result in adjacent portions becoming expanded due to a flow or displacement of material. Such materials are substantially non-porous and are of the type that may be advantageously employed as layer 29.

The present invention is described with respect to a three-ply panel, since such panels are in greater use than panels having more plies and which may be handled by the present apparatus in the same manner. As illustrated the panel 12 comprises an upper ply 30, a bottom ply 31, and a middle ply 32. For reasons of clarity of description, the upper and lower plies are differentiated although they are usually similar outer plies. In their manufacture, due care is taken to have at least one outer ply free of knot-holes. Consequently, except in the highest grades, the middle ply and, to a lesser degree, one of the outer plies, may have one or more knot-holes therein as hereinbefore indicated.

Referring now to Fig. 3, in which a conventional panel 12 is shown in the process of being embossed under pressure from elements 33 and 34, it will be seen that the portion 35 of ply 30 that is immediately above knot-hole 36, is unsupported. Consequently, the embossing lands 26, rather than impressing on the outer face of ply 30, depress said ply portion 35 into the void of the knot-hole. If the void 36 is in the bottom ply, the middle ply would offer little more effective support for the ply being embossed. Thus, such a panel would be defective in that, wherever there was a knot-hole, there would be either an unembossed area or a very shallow embossed area that interrupts the continuity of the embossments.

With more particular reference to Figs. 4 and 5, it will be seen that the portion 35 of ply 30, in the case of a knot-hole 36 in the middle ply, is firmly supported by the opposite portion 37 of the bottom ply 31. The heat from wall 25 is more readily transmitted to ply portion 37, than to other portions of ply 31, through the knot-hole. Therefore, because of moisture contained in said portion, the same is rendered more flexible than normal. Now, when a suitable pressure is applied, as by screws 18, to cause compression of roll layer 29, that portion of said layer which is directly beneath ply portion 37, will swell or expand and displace said portion in a direction toward ply 30. For all practical purposes, the expanded portion 38 of layer 29 is confined against further flowability or displacement by adjacent compressed portions of said layer. Hence, the practically incompressible thickened portion 38 supports inwardly flexed ply portion 37 and the latter, in turn, supports ply portion 35 so that the outer face of the latter will be embossed by lands 26 in the same manner and to substantially the same degree that the remainder of ply 30 is embossed.

The pressure that is applied between rolls 10 and 11 is in excess of that necessary for effecting proper embossment. This excess pressure manifests itself in considerable compression of layer 29 so that desired expansion of the portion 38 thereof is obtained.

As the panel 12 moves past the line of pressure application, such displaced portions 37 will spring back to approximately a coplanar alignment with the remainder of ply 31. It would not materially affect the panel should the return of portion 37 not be complete, since an almost imperceptible indent in the back panel would be the only result. Also, should ply part 35 be moved slightly toward ply part 37 in the process of embossing, an imperceptible shallowing of the embossments may result that would be immaterial to the general perfection of the panel.

From Fig. 6 it will be seen that a knot-hole 39 in the bottom ply will admit the expanded portion 38 of layer 29 to thereby support the middle ply 32 which, in turn supports the ply 30 that is being embossed.

From Fig. 7 it will be evident that lands 26 compress the fibres of ply 30 as indicated at 40. Those portions of said ply are, therefore, rendered harder than the initial hardness of said ply. The heat transmitted by wall 25, not only converts such moisture that may be present in ply 30 into steam to temporarily soften the ply to more readily be impressed by lands 26, but there is a dislodgement of both the wood fibres and the resin distributed among said fibres. While the fibres may be compressed, the resin, being substantially non-compressible, can only be displaced. Since this resin is displaced from beneath lands 26, it can only flow into those portions of the ply that are opposite the grooves 27 between the lands. Consequently, the high portions 41 of the embossments have an abnormally high resin content and are, therefore, also harder than the initial hardness of the ply. Since portions 41 are those exposed to greatest wear, such increased hardness improves the wear-resisting properties of the panel. The arrows shown in Fig. 7 suggest the direction of the forces that result in hardening of the ply.

Because of the compressibility of layer 29, as the panel 12 passes between the rolls 11 and 12, said layer, seeking to expand after compression, tends to curl the panel upward. The means 13 is provided for resisting and offsetting any curl that may thus tend to form. Said means may vary but, as shown, comprises a shoe 42 engaged with the face of the panel, one on each side of rolls 10 and 11. The pressure of shoe 42 may

be varied as by one or more pressure screws 44 to offset the tendency of the panel to curl as caused by compressive force on liner 29.

It will be seen that the present method obviates damage to the adhesive bonding the plies which may result in undesired blistering. Since, except at the high points of lands 26, the embossing pressure results in a lateral displacement of most of the wood fibres and of the heat-softened resins, there is little pressure directly toward the adhesive line that may tend to break the bond.

While the invention that has been illustrated and described is now regarded as the preferred embodiment, the construction is, of course, subject to modifications without departing from the spirit and scope of the invention. It is, therefore, not desired to restrict the invention to the particular form of construction illustrated and described, but to cover all modifications that may fall within the scope of the appended claims.

Having thus described the invention, what is claimed and desired to be secured by Letters Patent is:

1. The method for embossing only the upper surface of a plywood panel that has one or more knot holes in one of the plies other than the top ply, consisting in subjecting the plywood panel to roller pressure to effect an embossment on the upper surface of the panel, while a lower roller having a resilient surface is subjected to opposing pressure sufficient to simultaneously and temporarily largely fill the knot holes to support the upper surface substantially inflexibly during embossing.

2. The method for embossing only the upper surface of a three plywood panel that has one or more knot holes in the intermediate ply, consisting in subjecting the panel to roller pressure, to effect an embossment on the upper surface of the panel, while a lower roller having a resilient surface is subjected to opposing pressure sufficient to simultaneously and temporarily urge the portion of the bottom ply underlying the knot hole into said knot hole to largely fill the same and cause the upper surface of the bottom ply to contact the bottom face of the top ply in order to support the top ply during embossing.

3. The method according to claim 2 in which heat is applied to the ply being embossed and transmitted thereby through the knot hole to the bottom ply having the portion that is displaced to soften said portion for ready displacement into the knot hole by said opposing pressure.

4. The method according to claim 2 in which heat is applied to the ply being embossed to a degree sufficient to convert moisture in said ply into steam to temporarily soften said ply for ready compression and displacement of the wood fibres thereof while the same is being embossed.

5. The method for embossing the upper surface of a multi-ply plywood panel while leaving the lower surface substantially straight and unembossed, consisting in passing said panel between a hard embossing roll and a plane roll covered with a substantially non-compressible, but flowable material, and applying sufficient pressure between said rolls to cause said material to flow to unsupported locations where knot holes occur in the other plies below the upper ply in order to substantially uniformly support the upper ply during embossing of the upper surface.

6. The method for embossing the upper surface of a three plywood panel having one or more knot holes in the intermediate ply while leaving the lower surface substantially straight and unembossed, consisting in passing said panel between a hard embossing roll and a plane roll covered with a substantially non-compressible, but flowable material and applying sufficient pressure between said rolls to cause said material to flow to the unsupported locations underneath the knot holes and urge the portions of the bottom ply underlying the knot holes into said knot holes to largely fill the same and thereby support the upper ply during embossing, said bottom ply being constructed to have sufficient elasticity to cause said urged portions to return substantially to the plane of said bottom ply after embossing.

7. The method according to claim 6, in which heat is applied to the upper ply during embossing for transmission through the knot holes to the portions of the

bottom ply that are displaced in order to soften said portions for ready displacement into the knot holes.
